UNITED STATES PATENT OFFICE.

EVAN REESE, OF PLYMOUTH, PENNSYLVANIA, ASSIGNOR OF TWO-THIRDS
TO ENOS WILLIAMS AND J. P. BIEHL, OF SAME PLACE.

MINER'S SQUIB.

SPECIFICATION forming part of Letters Patent No. 672,650, dated April 23, 1901.

Application filed December 20, 1900. Serial No. 40,508. (No model.)

To all whom it may concern:

Be it known that I, EVAN REESE, a citizen of the United States, residing at Plymouth, in the county of Luzerne and State of Pennsylvania, 5 have invented new and useful Improvements in Miners' Squibs, of which the following is a specification.

My invention relates to miners' squibs, the same residing in a novel construction of the 10 squib itself and of the blank from which the squib is made.

The object of the invention is to provide a squib and the blank from which the same is produced by means of which the squib-tube 15 is effectively closed at its forward end and by means of which the fuse or match is formed integral with the said tube and projects outwardly therefrom at a short distance from the end of said tube, so that in the event of a 20 puncture of the forward end of said tube the explosive material contained therein will not fall upon and adhere to said match or fuse.

Other objects of the invention will herein-after appear and the novel features thereof 25 will be set forth in the claims.

In the drawings forming a part of this specification, Figure 1 is a face view of the blank from which my improved squib is made. Fig. 30 2 is a perspective view of the same, showing one edge of the blank rolled upon a mandrel as the first step in the formation of the tube. Fig. 3 is a similar view showing the closing-flap for the forward end of the squib-tube turned back into place and the blank, with the 35 mandrel therein, partially rolled on said flap.

Fig. 4 is a similar view of the blank, illustrating the tube-forming operation near its completion. Fig. 5 is a similar view showing the tube completely formed, with the outer edge 40 thereof pasted or otherwise secured in place.

Fig. 6 is a perspective view showing the match or fuse in its twisted condition, and Fig. 7 is a similar view of the completed squib.

Like reference-numerals indicate like parts 45 in the different views.

The blank 1 is provided with the parallel side edges 2 and with a tongue 4 and a lip or flap 5 at its forward end. The flap 5 is produced by a lateral incision 6, extending 50 inwardly from the side edge 2 of the blank, by a longitudinal cut 7, parallel to the side

edge 2 and intersecting the incision 6, and by an angularly-arranged incision 8, the latter forming one of the side edges of the flap 5 and a portion of one of the side edges of the 55 tongue 4. The incision 8 terminates at its rear end beyond the incision 6, as shown at 9, for a purpose which will presently appear. The side edge 10 of the tongue 4 directly opposite the incision 8 extends at an angle to 60 said incision and terminates at its rear end beyond the end of the incision 8, as shown at 11. From the point 11 to the side edge 3 of the blank the material thereof is cut away, as shown at 12. The lateral incision 6, extending inwardly from the side edge 2 of the blank 1, constitutes a guide for the end of the mandrel 13, upon which the blank 1 is rolled to form the squib-tube 14.

In forming the squib-tube the cylindrical 70 mandrel 13 is placed upon the upper surface of the blank 1, along the edge 2 thereof, with the end of said mandrel opposite the incision 6 in said blank. The edge 2 is then rolled upon the mandrel, as illustrated in Fig. 2 of 75 the drawings, until the partially-formed tube comes opposite the flap 5 adjacent to the longitudinal cut 7, which constitutes one of the side edges thereof. The said flap is then folded inwardly, as shown in Fig. 3 of the 80 drawings, closing the outer end of the partially-formed squib-tube, and the rolling of the blank upon the mandrel 13 is continued. This action causes the bent-in flap 5 to be rolled between the body of the blank 1 and 85 the outer surface of the partially-formed squib-tube. The same is thereby securely held in place, and danger of accidental separation thereof from the end of the squib-tube is prevented. In Fig. 4 of the drawings the 90 lip or flap 5 is shown as completely inclosed and covered by the partially formed tube; but the rolling of the blank 1 upon the mandrel 13 is continued until the edge 3 of said blank approaches said mandrel. The upper surface of the blank 1, adjacent to the edge 3, then has applied to it paste or other adhesive material, and when the blank is completely rolled upon the mandrel 13, as illustrated in Fig. 5 of the drawings, the squib-tube is completely formed, with the edge 3 of the blank 1 95 pasted or otherwise secured in place. The 100

tongue 4 has during this operation remained in practically flat condition, except, perhaps, along the line of its juncture with the body of the blank 1. As the point 9, however, 5 which is the rear end of the incision 8, is back of the incision 6, which is in line with the front end of the tube 14, it will be observed that the point or line of juncture of the tongue 4 with the body of the blank 1 is back of and 10 slightly removed from the forward end of the squib-tube. The point 11, which constitutes the rear end of the side edge 10 of the tongue 4, is slightly to the rear of the point 9, so that the line of juncture between the tongue 4 and 15 the body of the blank 1 is a diagonal one. The result of this construction is that when the tongue 4 is twisted to form the match or fuse 15 the same will connect with the body of the completed squib at a short distance 20 from the forward end thereof. By extending the side edge 10 of the tongue 4 back to the point 11, which is located to the rear of the point 9, said tongue when the article is 25 in the condition shown in Fig. 5 of the drawings will project slightly at an angle from the squib-tube and the twisting action upon the tongue 4 will have a tendency to roll said tongue around the projecting end of the squib-tube instead of at an angle, as shown 30 in Figs. 6 and 7.

Of course after the mandrel 13 has been removed from the tube which was formed thereon the said tube is filled with powder or other explosive material and the rear end thereof 35 closed in any suitable manner. Now it will be observed that as the closing-flap 5 is folded inwardly over the forward end of the partially-formed squib-tube and afterward rolled around the forward end of said tube said tube 40 is completely and effectively closed at its front end and none of the explosive contained therein can escape except by puncturing said closed end. In the event of such a puncture, however, and the consequent escape of the 45 powder or other explosive material from the forward end of the squib-tube none will come in contact with or adhere to the match or fuse 15, owing to the fact that said match or fuse is out of line with the body of the squib. An 50 effective closing of the tube is thereby formed by my construction, as well as an effective means for preventing accidents due to the escape of the explosive material from the tube.

The blank 1 may be made of tissue-paper 55 or other suitable material, and the match or fuse 15 may have paraffin or other suitable slow-burning combustible material thereon.

Having now described my invention, what I claim as new, and desire to secure by Letters 60 Patent, is—

1. A miner's squib having the match or fuse thereof secured to and projecting from the

tube at a point removed from the forward end thereof.

2. A miner's squib having the match or fuse 65 thereof secured to and projecting from the tube at a point removed from the forward end thereof, and extending out of line with said tube.

3. A miner's squib having the match or fuse 70 thereof integral with the tube and connected thereto at a point removed from the forward end thereof.

4. A miner's squib having the match or fuse 75 thereof integral with the tube and extending out of line therewith.

5. A miner's squib having the match or fuse thereof integral with the tube, the line of juncture between said match and tube being 80 diagonally arranged.

6. A blank for a miner's squib having at one end thereof, a tongue for the formation of the match or fuse, and a closing-flap, the rear end of the edge of said tongue adjacent to said flap lying at a point back of the rear end of 85 the opposite edge of said flap.

7. A blank for a miner's squib having at one end thereof a tongue for the formation of the match or fuse, and a closing-flap, the said flap being formed by a lateral incision leading inwardly from one of the side edges of 90 said blank, by a longitudinal cut intersecting said incision and by a longitudinal incision terminating at a point to the rear of said lateral incision.

8. A blank for a miner's squib having at one end thereof a tongue for the formation of the match or fuse, and a closing-flap, said flap 100 being formed by a lateral incision leading inwardly from one of the side edges of said blank, by a longitudinal cut intersecting said incision and by a longitudinal incision coincident with one of the side edges of said 105 tongue, the said longitudinal incision terminating at a point to the rear of said lateral incision, and the side of said tongue opposite said longitudinal incision being formed by a cut-away portion of said blank and terminating 110 at a point to the rear of the end of said longitudinal incision.

9. A miner's squib having the match or fuse thereof secured to and projecting from the tube at a point removed from the forward end 115 thereof, and coated with paraffin.

In testimony whereof I have hereunto set my hand in presence of two subscribing witnesses,

EVAN REESE.
